UNITED STATES PATENT OFFICE.

WILLIAM F. JOHNSON, OF BASIN, WYOMING.

COPY-HOLDER ATTACHMENT FOR TYPE-WRITERS.

1,209,589.

Specification of Letters Patent. Patented Dec. 19, 1916.

Application filed August 2, 1915. Serial No. 43,220.

To all whom it may concern:

Be it known that I, WILLIAM F. JOHNSON, a citizen of the United States, residing at Basin, in the county of Bighorn and State of Wyoming, have invented new and useful Improvements in Copy-Holder Attachments for Type-Writers, of which the following is a specification.

The invention relates to a copy holder, and more particularly to the class of automatic copy holder attachments for type-writers.

The primary object of the invention is the provision of a copy holder attachment of this character wherein the same is supported upon and travels with the carriage of the typewriter, and is automatically spaced by the platen of the latter for the word to word and line to line copying of the work when the typewriter is operated; thereby assuring accuracy in the reading of the work and the copying thereof.

Another object of the invention is the provision of an attachment of this character wherein the line spacing can be varied according to the spacing of the paper upon the platen of a typewriter, thereby assuring the proper feed of the writing to be copied, and avoiding the loss of the place in the copy while the typewriter is being operated.

A still further object of the invention is the provision of a copy holder attachment of this character wherein the writing to be copied is automatically fed therein correspondingly to the feeding of the sheets in the typewriter on actuating the keys thereof so that the writing to be copied can be read in a quick and convenient manner, and the loss of the place in the copy is entirely eliminated, the attachment being of novel form to assure the perfect working thereof.

A still further object of the invention is the provision of a copy holder attachment of this character which is simple in construction, thoroughly reliable and efficient in operation, readily and easily applied to various styles of typewriters, strong, durable, and inexpensive in manufacture.

With these and other objects in view, the invention consists in the construction, combination and arrangement of parts as will be hereinafter fully described, illustrated in

the accompanying drawings, and pointed out in the claim hereunto appended.

In the drawings: Figure 1 is a front elevation of a typewriter showing the copy holder attachment constructed in accordance with the invention applied. Fig. 2 is a top plan view thereof. Fig. 3 is an end elevation. Fig. 4 is an opposite end elevation. Fig. 5 is a fragmentary sectional view on the line 5—5 of Fig. 2. Fig. 6 is a sectional view on the line 6—6 of Fig. 2. Fig. 7 is a perspective view of the ratchet member showing the binding nut thereon.

Similar reference characters indicate corresponding parts throughout the several views in the drawings.

Referring to the drawings in detail, A designates the body of a typewriter, B the keys for actuating the type mechanism, C the movable carriage, and D the rotary platen journaled therein, which are of the ordinary well-known construction, while supported by the carriage is the automatic copy holder attachment hereinafter fully described.

The copy holder attachment comprises the upwardly convergent supports 10 which are arranged in pairs and are secured to opposite ends of the carriage C in any suitable manner, and have vertical uprights 11, and at the point of intersection of the respective supports 10 of the pairs is journaled the shaft 12 of a feed roller 13 which is located between the said pairs of supports, and about which is adapted to be trained the sheet containing the writing to be copied while the typewriter is being actuated. On one end of the shaft 12 carrying the roller 13 is a hand knob 14 which permits the manual turning of the roller when desired.

At one end of the platen D and movable therewith is a ratchet spacing wheel 15 as usual for the spacing of the said platen while the keys B and the spacer bar of the type mechanism are actuated in the ordinary well-known manner. Swingingly mounted upon the support 10 is a trip arm 16, which is supported by the pivot 17 passed therethrough and engaged in the said support, and upon this arm 16 is carried a ratchet member 18 which is adapted to engage the ratchet wheel 15, and this member 18 is ad-

justably locked in any suitable manner relative to the ratchet wheel 15 in a slot 18' in the arm 16, preferably by means of a binding nut 18^a, the said arm 16 being formed 5 with an elongated slot 19 in which is adjustably engaged the pivot 20 of a ratchet arm or dog 21, the same being formed with ratchet teeth 22 at its free end for tripping engagement with ratchet teeth 23 of a 10 ratchet spacing wheel 24 which is fixed to the shaft 12 supporting the feed roller 13 so that on the spacing of the platen D the feed roller 13 will be simultaneously spaced therewith for the automatic feeding of the sheet 15 having the writing to be copied on actuating the typewriter. It will be apparent that the arm 16 swings in an arc and during the upward movement of the said arm by one of the teeth on the ratchet wheel 15 engaging 20 with the member 18, the latter trips over the tooth engaged therewith when the arm reaches a predetermined elevation so that the spring 37 becomes active for the lowering of the arm 16 and the bringing of the member 18 in position with another tooth 25 on the wheel 15. In other words, when the arm 16 moves upwardly the member 18, following the arcuate movement of the said arm, rides off of the tooth engaged therewith 30 of the wheel 15 and is permitted to drop into engagement with another tooth of the wheel 15. This is due to the pivotal mounting of the arm 16 relative to the axis of rotation of the wheel 15, as will be apparent. By adjustment 35 of the pivot 20 in the slot 19 in the arm 16 the spacing of the feed roller 13 can be varied accordingly with the spacing of the platen of the typewriter, thereby permitting accuracy in the line to line writing from 40 the copy automatically fed by the roller 13 of the holder attachment.

Fixed to the uprights 11 and bridging the feed roller 13 is a bar 25 on which are adjustably mounted the paper guides 26 in the 45 free end of which is journaled the shaft 27 supporting the friction rollers 28 which serve to smooth the paper on the feed roller 13, and guide the same when trained about the said feed roller.

Arranged below the feed roller 13 is a 50 guide roller 29, the shaft 30 of which is journaled in arcuate shaped springs 31 which serve as hangers therefor, and are fixed to the top bar 25, and this roller 29 serves to 55 guide the paper onto the feed roller 13 from a paper rest 32 which is fixed to the supports 10 rearwardly of the said feed roller 13, and engaged with the ends of the shaft 30 are releasing levers 33, the same having pivotally 60 connected thereto toggle links 34 and 35, respectively, the links 34 being pivoted to the bar 25, while the links 35 are connected with the shaft 27 supporting the friction rollers 28, and by operating the levers 33

forwardly the said rollers 28 and 29 will be 65 automatically moved away from the roller 13 for the freeing of the paper containing the writing to be copied so that the said paper can be readily removed from about the feed roller as the occasion may require. 70

Fixed to one of the supports 11 and engageable with the ratchet wheel 23 is a resilient locking dog or pawl 36 which prevents the rotation of the feed roller 13 in one direction, yet the same is free to be rotated in a reverse direction. 75

Connected to the ratchet arm or dog 21 is a coiled retractile spring 37 which is also connected with one of the supports 10, and this spring serves to positively hold the 80 ratchet teeth 22 in engagement with the ratchet teeth 23 on the spacing wheel 24 for the positive spacing thereof when the platen D is spaced on the operation of the typewriter so that the sheet containing the writing to be copied will be automatically spaced correspondingly to the spacing of the sheet 85 being written upon in the typewriter when the latter is actuated.

Arranged forwardly of the carriage C and 90 platen D thereon, and fixed to the body A of the typewriter, is a stationary gage frame 38 having a scale bar 39 upon which is slidably fitted a pointer 40 which is adapted to aline with the letters constituting the words of the 95 writing to be copied so that as the carriage is advanced the pointer will indicate the letter of the word in the writing to be copied, and thereby assuring the accurate reading of the writing, and obviating the possibility 100 of the loss of the place when copying the same. The pointer 40 can be adjusted on the bar 39 to properly position the same for the starting point in the writing to be copied. 105

The typewriter is operated in the ordinary well-known manner, and also the paper is introduced and fed over the platen as usual. Now, on the movement of the carriage the copy holder is advanced therewith, 110 and when the platen in the carriage is rotated similar movement is imparted to the feed roller in the copy holder, so that the sheet containing the writing to be copied is fed thereby simultaneously with the spacing 115 of the platen.

From the foregoing description, taken in connection with the accompanying drawings, the construction and manner of operation of the device will be clearly understood, 120 and therefore a more extended explanation has been omitted.

What is claimed is:—

The combination with the platen carriage and platen of a typewriter, of an automatic 125 copy holder comprising supports fixed to the carriage, a feed roller journaled in the supports, a ratchet spacing wheel connected with

the feed roller, a trip arm swingingly mounted upon one of the supports, a ratchet member carried by said arm and adapted to be operated by the platen, said trip arm being formed with an elongated slot, an adjustable pivot engaged in said slot, a ratchet dog carried by said pivot and having ratchet teeth for engagement with the ratchet wheel, and resilient means connected with the sup-

port and the ratchet dog for holding the latter in operative relation to the ratchet wheel.

In testimony whereof I affix my signature in presence of two witnesses.

WILLIAM F. JOHNSON.
